UNITED STATES PATENT OFFICE.

STEPHEN SATTLER, OF TULSA, OKLAHOMA.

COPYHOLDER.

Application filed September 24, 1927. Serial No. 221,635.

The present invention relates to typewriter copy holders, and more particularly to an improved copy holder adapted for use with all standard makes of typewriters and adapted to be collapsed so as to fit in any one of the common makes of typewriter desks.

Although there are a great many types of typewriter copy holders on the market at the present time, still there is no practical holder available to the public that can be collapsed into a desk along with the typewriter. In general, the holders that are most universally used are cumbersome, unwieldy and unhandy. Many of the holders are not capable of receiving different widths of paper. Moreover, a great majority of the holders are not capable of making the regular one, two and three spacings on the copy to conform with the spacings used on the typewriter in making the copy.

An object of the present invention is to provide a copy holder capable of use with any standard make of typewriter.

Another object of the present invention is to provide a collapsible copy holder adapted to be collapsed into any of the standard makes of typewriter desks.

Another object of my invention is to provide a copy holder having a revolvable cylinder paper feeder that is capable of accommodating from 6" to 20" width paper and above.

Still another object of the invention is the provision of a copy holder including a revolvable cylinder wherein the copy is suspended in a perpendicular position from the cylinder; all of the copy being open to vision.

A further object of the invention is to provide a perpendicular copy holder that will collapse and expand readily and without screwing and unscrewing hand screws, or a great deal of trouble and time.

A still further object of my invention is the provision of a copy holder capable of making a regular one, two and three spacings on the copy similar to the spacings used on the typewriter in making the copy.

Other objects and advantages of my invention will more fully appear from the following detailed description taken in connection with the accompanying drawings, which illustrate a single embodiment thereof, and in which:

Figure 1 is a front elevation of my copy holder;

Figure 2 is a side view of the copy holder shown in Figure 1;

Figure 3 is a plan view of the base of the copy holder taken on substantially the line III—III of Figure 1 looking downwardly 60 and shown partly in section;

Figure 4 is an enlarged sectional view taken on substantially the line IV—IV of Figure 1 looking in the direction indicated by the arrows; 65

Figure 5 is a plan view of the copy holder shown in Figure 1;

Figure 6 is a fragmentary view drawn to an enlarged scale partly in section and taken on substantially the line VI—VI of Figure 1 70 looking in the direction indicated by the arrows, and

Figure 7 is a fragmentary sectional view drawn to an enlarged scale and taken on substantially the line VII—VII of Figure 6. 75

In the drawings:

Like reference characters designate similar parts throughout the several views.

The reference character 10 designates generally the base of the copy holder and comprises a channeled sheet metal construction, as is clearly evident from Figure 3. This base includes a pair of parallel laterally extending arms 11 and 12 and a connecting portion 13 disposed between the arms. Secured to the connecting portion 13 are a pair of vertical upright rods 14—14. These rods are spaced from each other and are parallel to each other. It is upon these rods, as will become more apparent hereinafter, that the 80 upper frame portion of the copy holder is adapted to slide. 85

The upper frame of the copy holder includes a pair of spaced vertical support members 15—15, each of which includes an 90 inwardly turned ear 16 having an opening 17 through which a rod 14 extends. It will thus be evident that the two support members 15—15 are slidably mounted upon the rods 14—14. The upper end of each of the support members 15 has formed integral with it a laterally extending arm 18 (Figure 4). A spacing rod 19 rigidly connects the two arms 18—18 together. These two arms 18—18 95

rotatably carry a paper feed cylinder 20 which may be of the same construction as the platen on a typewriter. This platen includes a shaft 21, the ends of which are journaled in the two spaced arms 18—18 of the frame members 15—15. Also the cylinder 20 100

110

includes a rubber covering 22 in order to prevent slippage between the paper on the cylinder and the cylinder.

Associated with each support rod 14 is a locking member 24 having formed integral with its lower end an ear 25 secured to the adjacent support member 15. Since each of the locking members 24 is identical in construction to the other locking member, it is thought that a description of one will suffice for both. Also secured to the ear 25 of the locking member is a pin 26 which carries a small leaf spring 27 having its upper end in engagement with the vertical or resilient portion 28 of the locking member (Figure 4). Formed integrally with the upper end of the resilient portion 28 is a lateral arm 29 having secured to its underside a stop block 30. The under surface of the block 30, as shown in Figure 4, is adapted to normally contact the upper end of the associated support rod 14. One side of the block 30 abuts a leg 31 of an angular piece 32 secured to the associated support member. This angular piece 32 insures that the stop block 30 will be properly aligned with the upper end of the support rod 14.

In order to permit the two support or frame members 15 to be moved downwardly upon the support rods 14, it is necessary that the locking members 24 be each moved out of the path of the upper end of the associated rod 14. In other words, each locking member must be moved to a disengaged position such as that indicated by dotted lines in Figure 4. I shall now describe the manually operable release mechanism for moving these locking members 24 to their disengaged positions.

Extending transversely of the copy holder and disposed substantially parallel to the base 10 is a release rod 35 having its ends rotatably mounted in the two spaced frame members 15-15. Each end of this rod 35 is bent so as to provide two laterally extending U-shaped projections 36-36 cooperable with the two lock members 24-24. Normally these U-shaped projections 36 are disposed in a vertical plane, as best shown in Figure 4. One of the extreme ends of this rod 35 is also provided with an arm or handle 37 disposed adjacent the outer surface of one of the support members 15 (Figure 1). Now when it is desired to move the locking members 24 out of cooperation with the upper ends of the two support rods 14-14, the same may be accomplished by merely turning the handle 37 so as to bring each of the U-shaped projections 36 into a dotted position such as that shown in Figure 4. Each projection 36 in assuming this horizontal position strikes the resilient vertical leg or portion 28 of the associated locking member 24 and moves the upper end of the locking member laterally away from the rod 14. Obviously this movement

of each of the locking members 24 results in the compression of the associated leaf spring 27. It, therefore, follows that when the handle 37 is returned to its normal position, the leaf springs 27 will become effective to urge the locking members 24 back to their engaged positions. When the locking members 24 are in their disengaged positions, the upper frame members 15-15 and the cylinder 20 move downwardly due to gravity to the dotted position shown in Figure 1. The upper frame structure including the frame members 15 may be returned to their operative position by raising the same a sufficient extent to permit return of the locking members 24 to engaged positions.

I shall now proceed to describe in detail the mechanism for indexing the cylinder 20. Secured to one end of the shaft 21 of the cylinder 20 is a ratchet wheel 40 disposed adjacent the outer surface of one of the arms 18, as shown in Figure 7. Secured to this arm 18 is a pin 41 which supports a leaf spring 42, the lower end 43 of which engages the teeth of the ratchet wheel 40. The purpose of this leaf spring 42 is to prevent the ratchet wheel from being turned in a counter-clockwise direction as viewed in Figure 6.

Positioned between the ratchet 40 and the associated arm 18 is a plate 44 loosely mounted upon the shaft 21. This plate has three small openings or holes 45, 46 and 47 cooperable with a ball 48 mounted in an opening 49 in the associated arm 18 (Figure 7). One side of the opening 49, as best shown in Figure 7, is normally maintained closed by means of a leaf spring 50 secured by a screw 51 to the arm 18. This leaf spring 50 serves to resiliently urge the ball 48 into cooperation with the plate 44. The ball 48 is adapted to engage in any one of the three holes 45, 46 and 47, depending upon the particular spacing required, as will be more fully explained hereinafter. Formed integrally with the plate 44 is an offset laterally extending arm 52 adapted to be manually engaged to rotate the plate 44 upon the shaft 21. This offset arm 52, as best shown in Figure 2, includes a handle 53 arranged away from the periphery of the cylinder 20 where it is readily accessible. Formed integrally with the plate 44 is a shoulder 54 adapted to engage a stop pin 55 secured to the associated arm 18 to limit the movement of the plate 44 about the axis of shaft 21.

The offset arm 52 has secured to an intermediate portion thereof an inwardly extending pin 56 adapted to be engaged by the curved surface 57 (Figures 5 and 6) of detent or pawl arm 58. The upper end of this arm 58 is pivotally mounted upon a pin 59 secured to the bent upper end 61 of a reciprocating rod 60. The lower end 62 of this arm 58 is adapted to engage the teeth of the ratchet wheel 40 to index the cylinder 20.

Formed integrally with the arm 58 is a laterally extending arm 63 which has secured to its free end one end of a spring 64. The other end of the spring 64 is secured to the 5 spacing rod 60. The position of arm 58 is determined by the position of the pin 56 which is connected to the arm 52. Obviously when the ball 50 is in the opening 45 in the 10 plate 44 the pin 56 will be disposed in its uppermost position thereby enabling the arm 58 upon an operation thereof to index the ratchet three teeth causing the cylinder to make what is usually termed a triple space. On the other hand, when the ball 50 is in co- 15 operation with the opening 46, the pin 56 will have been moved to its intermediate position whereby the arm 58 will be permitted to index the ratchet wheel two teeth, thus causing the cylinder 20 to make a double 20 space. Furthermore, when the plate 44 is moved so as to bring the opening 47 into co-operation with the ball 50, the arm 58 will be caused to index the ratchet 40 one tooth whereby the cylinder 20 will make a single 25 space.

The plate 44 has a projection 44^a adapted upon the rotation of plate 44 in a counter-clockwise direction to move the end 43 of the leaf spring 42 out of cooperation with the 30 teeth of the ratchet wheel 40, whereby it is possible to rotate cylinder 20 any degree desired independently of the ratchet teeth. The turning of the plate 44 in a counter-clockwise direction is accomplished by merely raising 35 the arm 52 connected thereto. Thus, it will be evident that the leaf spring 42 may be disconnected with facility from the ratchet wheel 40.

It will, of course, be understood that the 40 operation of the arm 58 is dependent upon the downward movement of the spacing rod 60. This rod 60 extends downwardly alongside one of the support members 15 and has formed integral with it an offset portion 65 having an elongated slot 66 (Figure 2). Extending into the slot 66 is a pin 67 secured to the upper end of a vertical rod 68. The purpose of the slot 66, as will more fully appear hereinafter, is to allow for the collapsing of 50 the upper frame part upon the two rods 14-14. The spacing rod 60 is also provided with a pair of guide slots 69 and 70 (Figure 2) into which extend pins 71 and 72 secured to the adjacent frame member 15. These pins 55 71 and 72 travel in the slots of the rod 60 to guide the rod in its vertical movement. Secured at one end to the upper end of the offset portion 65 is a return spring 73, the upper end of which is secured to a pin 74 secured to the adjacent support member 15. This spring 60 functions after each downward movement of the spacing rod 60 to return it and the associated parts to their normal positions. The lower end of the vertical rod 68 is pivotally attached to one end of a lever 75 pivotally

connected between its ends to a lug 76 formed integrally with arm 12 of the base 10. The other end of the lever 75 is pivotally connected to one end of an operating lever 77. An intermediate portion of this operating lever 70 75 is pivotally connected to a lug 78 also secured to arm 12 of base 10. The other end of the operating lever 77 (Figure 3) is provided with a finger portion 80 adapted to be engaged to operate the spacing rod 60. It will 75 thus be evident that upon the depression of the finger portion 80 of lever 77, the spacing rod 60 will be pulled downwardly causing the operation of arm 58 to turn the ratchet 40 whereby the cylinder 20 is indexed a pre-determined degree. 80

I shall now proceed to describe in detail the mechanism for holding the paper to be copied in cooperation with the cylinder 20. Extending transversely of the base 10 and secured at its ends to the arms 11 and 12 of the base is a rod 81. Pivotally mounted upon this rod 81 (Figures 1 and 4) is a vertically extending paper guide member 82 disposed parallel to the support rods 14-14. Formed 90 integrally with this member 82 is a laterally extending arm 83 disposed at right angles to the member 82 proper. This arm 83 is disposed parallel to the plane of the base 10 and extends through a guide slot 84 in the 95 flange of the connecting portion 13 of base 10. Extending through an opening in the arm 83 is a vertical pin 85 secured at its lower end to the intermediate or connecting portion 13 of the base 10. A collar 86 surrounds the 100 pin 85 and is disposed between the bottom of the base 10 and the arm 83 (Figure 4). This collar 86 is normally engaged by the under surface of the arm 83. Also surrounding the pin 85 is a spring 87 which serves to at all 105 times urge the arm 83 downwardly into cooperation with the collar 86. The upper end of the spring 87 abuts an adjusting nut 88 threaded upon the upper end of the pin 85.

Slidably mounted upon the upper end of 110 the vertical member 82 is a tubular block 90 to which is rigidly secured a pair of upwardly extending diagonal elements 91 and 92. The upper ends of these two diagonal elements 91 and 92 are rigidly fastened to a 115 straight-edge or line indicating strip 93 disposed in front of the periphery of the cylinder 20. The top edge of this strip is adapted to be disposed directly below the line which is being copied at any one time. Also secured to the strip 93 are a pair of curved paper guides 94 and 95 which extend over the periphery of the cylinder 20. Fastened to an intermediate portion of the strip 93 is a handle 96 by means of which the strip may be 120 pulled laterally away from the periphery of the cylinder 20. Rotatably mounted in the strip 93 are a pair of rollers 97 and 98 adapted to engage the periphery of the cylinder 20 or the surface of the paper extending over the 130

cylinder 20. The two guides 94 and 95 are reinforced by a connecting rod 99, as shown in Figure 1. Attention is directed to the fact that the two diagonal elements 91 and 92 are bent outwardly so as to pass up around the periphery of the cylinder 20, as best shown in Figures 2 and 4.

The tubular block 90 is adapted to normally have its upper end in engagement with a stop pin 101 secured to the upper end of the vertical member 82. Fastened to one side of the block 90 is a leaf spring 102 having its lower end bent inwardly toward the member 82, as indicated at 103. The bent end 103 of the leaf spring 102 is adapted to engage in a notch 104 in the member 82. Also secured to the leaf spring 103 is a lateral extension or finger piece 104' adapted to be depressed in a direction toward the block 90 whereby the bent end 103 of the leaf spring 102 can be moved out of cooperation with the notch 104 in the member 82 to permit the block 90 sliding downwardly upon member 82. In other words, by releasing the leaf spring 102 from cooperation with the member 82, the diagonal elements 91 and 92 and the straight-edge strip 93 will gravitate to the dotted position shown in Figure 1.

At this time I wish to direct attention to the fact that shaft 21 of the cylinder 20 also has secured to its end a knob 100 of the same construction as the knob employed on the platen of the conventional typewriter. It will thus be obvious that the cylinder 20 may be actuated independently of the spacing rod 60 by merely turning the knob 100.

The operation of my novel copy holder is believed to be evident from the foregoing detailed description and I shall therefore touch upon only the more important phases of the operation of the device. The device is disposed in a position in the rear of the typewriter and directly in front of the typist. The paper to be copied is inserted between the roll 20 and the diagonal struts 91 and 92. The first line on the paper is brought into a position where it is directly above the strip 93. It will therefore be apparent that the paper is suspended in a perpendicular position from the indexing mechanism, namely, the cylinder 20. After the line has been copied by the typist, the cylinder is indexed by merely depressing the finger portion 80 of the lever whereupon the sheet is moved upwardly a distance fixed by the spacer. The spacing made by the cylinder 20 depends upon the position of the arm 52, as previously described. After the work has been copied, the paper is removed from the device and the device is telescoped. By telescoping I mean the lowering of the upper frame of the device upon the rods 14-14 to the dotted position shown in Figure 1. It will, of course, be evident that the straight-edge 93 and the diagonal elements 91 and 92 connected thereto are

lowered independently of the frame members 15-15.

Now I desire it understood that although I have illustrated and described in detail the preferred form of my invention, the invention is not to be thus limited, but only in so far as defined by the scope and spirit of the appended claims.

I claim as my invention:

1. In combination, in a copy holder of the character described, a telescopic frame, means for advancing the paper to be copied mounted upon the upper end of the frame, and means for holding the paper in contact with said advancing means whereby the paper is suspended in a perpendicular position from the advancing means, said last mentioned means being telescopically supported independently of said frame.

2. In combination, in a copy holder of the character described, a collapsible frame, means for advancing the paper to be copied mounted upon the upper end of the frame, and means for holding the paper in contact with said advancing means whereby the paper is suspended in a perpendicular position from the advancing means, said frame and said latter means being collapsible to permit the copy holder being housed in a typewriter desk.

3. In combination, in a copy holder of the character described, a collapsible frame, means for advancing the paper to be copied mounted upon the upper end of the frame, and means for holding the paper in contact with said advancing means whereby the paper is suspended in a perpendicular position from the advancing means, said last mentioned means being telescopically supported independently of said frame and said frame being collapsible independently of said latter means.

4. In combination, in a copy holder of the character described, a frame comprising telescoping parts adapted to be collapsed one upon another, a rotatable cylinder connected to the top of the frame from which the paper to be copied is suspended in a vertical position, said cylinder being adapted to advance the paper upwardly, means connected to the lower part of the frame for operating said cylinder, telescopic connections between said latter means and the cylinder extending alongside of the frame, and means for retaining paper against said cylinder, said latter means being telescopically supported for collapse independently of said first mentioned means.

5. In combination, in a copy holder of the character described, a frame comprising telescoping parts adapted to be collapsed one upon another when the holder is in disuse, and means for advancing the paper along said frame connected to the upper part of

- the frame including a rotatable cylinder from which the paper to be copied is suspended in a vertical position, a ratchet for indexing said cylinder connected to an end of the cylinder, 5 telescopic linkage for operating said ratchet extending downwardly alongside of said frame and telescopically collapsible co-extensive with said frame, an operating lever connected to said linkage for operating the linkage, 10 said lever being mounted upon the lower part of the frame, and means telescopically associated with said holder for retaining paper against said cylinder, said last mentioned means being telescopically collapsible 15 independently of said linkage.
6. In combination, in a copy holder of the character described, a frame comprising telescoping parts adapted to be collapsed one upon another when the holder is in disuse, 20 means for advancing the paper along said frame connected to the upper part of the frame including a rotatable cylinder from which the paper to be copied is suspended in a vertical position, collapsible means for holding 25 the paper in contact with the periphery of said cylinder including a straight-edge strip disposed parallel to the cylinder, and telescopic supporting means for said strip collapsible independently of said frame.
- 30 7. In combination, in a copy holder of the character described, a frame comprising telescoping parts adapted to be collapsed one upon another when the holder is in disuse, means for advancing the paper along said 35 frame connected to the upper part of the frame including a rotatable cylinder from which the paper to be copied is suspended in a vertical position, and collapsible means for holding the paper in contact with the periphery 40 of said cylinder including a straight-edge strip disposed parallel to the cylinder, said collapsible means including a plurality of telescoping parts, one of which is adapted to be moved downwardly on the other when 45 the means is collapsed, said frame and said strip holding means being independently collapsible for permitting storage of said copy holder with a typewriter.
8. In combination, in a copy holder of the 50 character described, a frame including upper and lower parts, said upper frame part comprising connected vertical uprights, advancing means carried by said vertical uprights for advancing the paper to be copied, said 55 lower frame part including a base carrying vertical rods telescoping the uprights spring means secured to the upper part for engaging over the upper ends of the lower part for locking said parts in extended position, and a rod for releasing said lock means whereby said upper part may be collapsed upon the lower part.
9. In combination, in a copy holder of the 60 character described, a frame including upper and lower parts, said upper frame part com-
- prising connected vertical uprights, advancing means carried by said vertical uprights for advancing the paper to be copied, said lower frame part including a base carrying vertical rods telescoping the uprights, spring 70 means secured to the upper part for engaging over the upper ends of the lower part for locking said parts in extended position and a rod for releasing said lock means whereby said upper part may be collapsed upon the 75 lower part, said lock means including spring locking elements secured to the uprights of the upper frame for hooking engagement with the upper ends of the rods of the lower frame.
- 80 10. In combination, in a copy holder of the character described, a frame including upper and lower parts, said upper frame part comprising connected vertical uprights, advancing means carried by said vertical uprights 85 for advancing the paper to be copied, said lower frame part including a base carrying vertical rods telescoping the uprights, spring means secured to the upper part for hooking over the upper ends of the lower part for locking said parts in extended position, and means for releasing said lock means whereby said upper part may be collapsed upon the lower part, said release means including a 90 transverse rod having its ends mounted in 95 said uprights adjacent said locking means.
11. In combination, in a copy holder of the character described, a frame including upper and lower parts, said upper frame part comprising connected vertical uprights, advancing means carried by said vertical uprights for advancing the paper to be copied, said lower frame part including a base carrying vertical rods telescoping the uprights, means 100 for locking said parts in their extended positions, and means for releasing said lock means whereby said upper part may be collapsed upon the lower part, said lock means including locking elements secured to the uprights adapted to engage the upper ends of said rods, said release means including a transverse rod having its ends mounted in said uprights adjacent said locking means, said release rod including lateral projections adapted to strike said locking elements to 110 move them out of cooperation with said vertical rods.
- 115 12. In combination, in a copy holder of the character described, a frame, means for advancing the paper to be copied mounted upon the upper end of the frame, and means for holding the paper in contact with said advancing means whereby the paper is suspended in a perpendicular position from the advancing means, said holding means being collapsible and including a rod pivotally mounted at its lower end upon the base of said frame, a tubular member telescoped by said rod adapted to slide on said rod when said holding means is collapsed, and a line indi- 120 125 130

cating strip connected to and carried by said tubular member disposed in proximity to said advancing means.

13. A copy holder comprising a base and 5 a platen, telescopic supports for said platen carried by said base, a copy line guide along and adjacent said platen, means carried by said base for telescopically supporting said guide, releasably locking means for allowing 10 collapse of said guide, and other releasably locking means for collapsing said platen support.

14. A copy holder comprising a base and 15 a platen, means for imparting step by step movement to said platen, said means comprising a shaft, a ratchet wheel on said shaft, a plate on said shaft adjacent said wheel and rotatable relatively thereto, a frame mem-

ber supporting said shaft and bearing against said plate, said frame member carrying a 20 ball projecting from the face of said member against said plate, said plate having a plurality of openings lying in an arc, the radius of which is the distance from said shaft to the center of said ball for selective cooperation with said ball whereby the angular position of said plate may be varied, and a longitudinally movable spacing rod having a pawl thereon for engaging said ratchet wheel, said plate having an arm thereon provided 25 with a stop for said pawl whereby angular movement of said ratchet by said pawl is controlled by the angular position of said arm.

In testimony whereof I have hereunto subscribed my name.

STEPHEN SATTLER.
